UNITED STATES PATENT OFFICE.

ROYAL W. CATHCART AND JOHN P. CARPENTER, OF ELKHART, INDIANA.

MUSIC-RACK.

1,167,383.

Specification of Letters Patent.

Patented Jan. 11, 1916.

Application filed December 23, 1913. Serial No. 303,363.

To all whom it may concern:

Be it known that we, ROYAL W. CATHCART and JOHN P. CARPENTER, citizens of the United States, residing at Elkhart, 5 county of Elkhart, and State of Indiana, have invented a new and useful Music-Rack, of which the following is a specification.

Our invention relates to improvements in music racks and particularly to a type of 10 music rack which has a revoluble frame for holding the sheet of music, and which permits of reading the music on a sheet secured therein on both obverse and reverse sides thereof without the removal, or turning, 15 of the sheet of music.

The objects of our invention are, first, to provide a revoluble music rack, or frame, whereby both the obverse and reverse sides 20 of a sheet of music may be read without removing the sheet of music from the frame; second, to afford facilities for the adjustment of the upper frame arms to accommodate various sizes of sheet music. We attain 25 these objects by the mechanism illustrated in the accompanying drawings, in which—

Figure 1 is a front elevation of the entire music rack. Fig. 2 is a side elevation thereof with the revoluble base member shown in fragmentary section. Fig. 3 is a plan view 30 of the lower end of the base member, revoluble on a non-revoluble standard. Fig. 4 is a rear elevation of the music rack with the lower locking arms open and the upper locking arms closed. Fig. 5 is a fragmentary plan view of the outer end of a lower arm member, showing the lug for receiving the lower locking arm.

Similar figures refer to similar parts throughout the several views.

The invention consists essentially of a 40 non-rotative frame support 1, and a rotative sheet music holding frame pivotally mounted thereon. The rotative frame embodies generally, a frame shaft consisting of base member 4 and shaft 5 rigidly fastened together for pivotal operation, the sleeve member 6 carrying upper arm supports and upper frame arms 19 and 20 mounted thereon, lower frame arms 25 and 26 mounted 45 upon the frame shaft base, upper locking arms 23 and 24, an upright swinging clamp 10 hinged at the shaft base, and lower locking arms 30 and 31 pivotally mounted on the clamp member 10.

On the drawings, 1 is the bearing standard 55 which is non-revoluble and carries the entire

music rack frame. Its lower end may be attached to any suitable base plate or tripod. Its upper end is the pivot shaft upon which the music rack revolves, and which projects 60 into the socket 14 of the base member 4. working freely therein to insure ease of revolution. On one side of member 1 is fastened a spring pawl 2, being secured in position by the screw 3. It projects upward 65 and is adapted to engage either one of the two oppositely disposed slots 15 formed in the outer periphery of the annular base member 4 when the same is in alinement with the slot 16 which is formed on one side 70 of the annular enlargement of member 1. When arranged within slot 16 any lateral movement of the pawl 2 is arrested. Shaft 5 is firmly fixed in base member 4 by pin 38. At its top is locking spring 8 held in position by screw 9. The T shaped member 4 has supporting arms 25 and 26 fastened to it by pins 36 and 37 which permit of free action upward on the part of arms 25 and 26. Normally, arms 25 and 26 rest upon the 80 brackets 17 and 17 which are lateral projections from member 4. Lugs 28 and 29 are formed at the outer end of arms 25 and 26, which are preferably of angle iron.

Attached to the base member 4 and in 85 hinged relation therewith is the clamping member 10 the upper end of which is adapted to be locked against the shaft 5 by the locking spring 8. This member 10 has a hinge 11 fastened to its lower end, which in 90 turn is fastened to the lower end of member 4, in hinged relation, by the pin 12, permitting of free and easy backward and forward movement of the entire member 10 when disengaged with spring 8. When member 10 95 is locked against the shaft 5 by the spring 8 it is in the position indicated by the dotted lines 39. Fastened to clamp member 10 is the locking arm 30 held by the pin 33. And attached to locking arm 30 is locking arm 31 100 held to arm 30 by the pin 32. Arms 30 and 31 are preferably of flat metal, freely movable at the pins 32 and 33, collapsible against member 5, and adapted to be secured, at their outer ends, by the lugs 28 and 29 at the outer end of members 25 and 26.

Shaft member 5 is preferably of rectangular section to prevent a circular motion of the sleeve arm bearing member 6 which is adjustably mounted on said shaft 5 and 110 which may be set and fixed in any desired position thereon by the use of the set screw

2
7. Fastened to sleeve member 6 are arms 19 and 20, preferably of flat metal, and held to 6 by pins 21 and 22 upon which they are freely movable upward and downward to a 5 horizontal plane. The pins 18 and 18 set in member 6 prevent arms 19 and 20 from falling below a point at right angles to member 5. Attached to arms 19 and 20 by pins 34 and 35 and freely movable on same 10 are retaining arms 23 and 24, preferably of flat metal, somewhat bowed, and in concave relation to arms 19 and 20 when parallel therewith. Frame arms 19, 20, 25 and 26 freely fold upwardly on the pins 22, 21, 36 15 and 37, respectively, to reduce the bulk of the complete frame and to enable its ready transportation.

To place and clasp a sheet of music in the rack, or frame, the various members and 20 parts are operated as follows: Clamp member 10 is disengaged from the locking spring 8 and drawn away from the shaft 5; arms 30 and 31 are lifted upward out of engagement with lugs 28 and 29 and placed in 25 about the position shown in Fig. 1; retaining arms 23 and 24 are forced upward at right angles to arms 19 and 20. The frame is then wide open, and the sheet of music is inserted between members 10 and 5 and 30 brought forward and downward until the lower end thereof rests upon the flat surface 27 of the arms 25 and 26. Member 10 is then pressed forward against the sheet of music, which is clamped between shaft 5 35 and member 10 thereby, and the upper end of 10 forced into engagement with locking spring 8 which holds it firmly against the sheet of music. Retaining arms 23 and 24 are then drawn downward and outside of 40 the sheet of music until practically parallel with arms 19 and 20, thereby firmly holding the upper outside corners of the sheet of music. Finally, the arms 30 and 31, which are carried by member 10 and movable therewith, 45 are drawn downward and the outer ends thereof pressed into the hook formed by the lugs 28 and 29, thereby firmly holding the outside lower corners of the sheet of music. To rotate the entire frame the spring 50 pawl 2 is retracted from slot 15. The frame is then freely revoluble upon the pivot end of member 1 arranged within the socket 14, and may be rotated either way. If pawl 2 is held retracted the frame may be 55 rotated any number of times. But if not so held retracted, the pawl 2 will spring forward into the slot 15 which first alines with slot 16 and thereby locks the frame against further rotation until again retracted.

60 What we claim is:—

1. A sheet music rack comprising a non-rotative frame support, a frame shaft

mounted upon said frame support and in pivotal relation therewith, a sleeve member 65 adjustably mounted upon said frame shaft having frame arms thereon and clamps on said arms, frame arms mounted at the base of said frame shaft and revoluble therewith, a swinging clamping member mounted upon said frame shaft base, means for locking one 70 end of said clamping member to said frame shaft, and means for arresting rotation of said frame shaft after rotation thereof.

2. In a music rack, the combination of a non-rotative frame support and a rotative 75 music holding frame pivotally mounted upon the frame support, said music holding frame comprising in combination, a frame shaft having its base arranged in pivotal relation to said frame support and mounted 80 thereon, a swinging clamp member mounted upon said frame and rotative therewith, lower frame arms mounted upon the frame shaft base and pivotally connected therewith, locking arms mounted upon the clamp 85 member and adapted to coöperate with said lower frame arms, means for locking one end of said clamp member, and means for arresting rotation of said frame after rotation thereof. 90

3. In a music rack, the combination of a non-rotative frame support and a rotative music holding frame pivotally mounted upon the frame support, said frame comprising in combination a frame shaft, a 95 clamping member mounted thereon and rotative therewith, lower frame arms pivotally connected with said frame shaft, said arms having lugs at their outer ends, locking arms pivotally mounted upon the clamping member and adapted to engage the lugs on said frame arms, and means for locking the clamping member at one end thereof. 100

4. A music rack comprising a non-rotative frame support and a rotative frame 105 pivotally mounted thereon, said rotative frame comprising in combination, an inclined frame shaft, a sleeve adjustably mounted thereon, collapsible supporting arms carried by said sleeve and a clamp mounted upon each of said arms, a swinging rotative clamp member mounted upon said shaft and means for locking one end thereof, locking arms mounted upon said clamp member, collapsible arms mounted at 110 the base of said inclined shaft and adapted for coöperation with said locking arms, and means for arresting rotation of said frame after rotation thereof. 115
